UNITED STATES PATENT OFFICE.

ALBERT E. BEEBE, OF CATHAY, NORTH DAKOTA.

PROPELLUTION MEANS FOR FLYING MACHINES.

Application filed January 31, 1922. Serial No. 533,029.

To all whom it may concern:

Be it known that I, ALBERT E. BEEBE, a citizen of the United States, and a resident of Cathay, in the county of Wells and State 5 of North Dakota, have invented certain new and useful Improvements in Propulsion Means for Flying Machines, of which the following is a specification.

The present invention relates to an improvement in propulsion means for flying machines.

The object of the invention is to provide an improved propulsion means of this character which is adapted to propel the flying 15 machine either forwardly or upwardly, the direction of travel of the flying machine being thus readily varied by varying the character of the action of the propulsion means and the propulsion means being readily controllable for this purpose.

Another object is to provide a propelling means of this character which may be utilized to retard the descent of the plane.

Another object is to provide propelling 25 means for flying machines which is of simple and durable construction, reliable and efficient in operation and easy and inexpensive to manufacture and operate.

Other objects and advantages of the invention reside in certain novel features of construction, combination and arrangement of parts which will be hereinafter more fully described and particularly pointed out in the appended claims, reference being had 35 to the accompanying drawings forming part of this specification, and in which:

Figure 1 is a plan view of a flying machine equipped with the propulsion means constituting the present invention;

Figure 2 is a detail view in side elevation, illustrating the propulsion means positioned for propelling the aeroplane forwardly;

Figure 3 is a similar view, showing the propelling means positioned to lift the aeroplane to propel it upwardly as well as forwardly;

Figure 4 is a detail perspective view of one combined stop and guide for the propeller blades;

Figure 5 is a plan view, showing a slightly different mode of organizing the propelling means of a flying machine.

Referring to the drawings wherein for the sake of illustration is shown the preferred 55 embodiments of the invention and more particularly to Figures 1 to 5, the numeral 10

designates generally a flying machine which may be of any suitable type and which preferably includes a fuselage 11 organized with planes 12 in any improved manner. The 60 fuselage has a rudder 13 arranged at the rear thereof and the planes may be equipped with ailerons or other controlling devices.

The propulsion apparatus which constitutes the present invention is preferably in 65 a number of units which may be organized with the flying machine in any desired manner.

In the arrangement shown in Figure 1, a unit is arranged at the forward or bow end 70 of the aeroplane, as designated at 15, and a pair of units designated at 16 and 17 are arranged at the rear end or tail end of the machine. As these propelling units are of identical construction in all major respects 75 a common description will serve for all.

Each propelling unit includes a stationary or main frame 20 suitably supported and organized with the fuselage of the flying machine. A movable frame 21 is arranged within the main frame 20, and is adjustably 80 supported thereon by means of a supporting shaft 22 which is journaled in suitable bearings provided therefor in the main frame and which is associated with the movable frame by means of a pair of rings or spiders 85 24 secured to the members of the movable frame and having hubs 25 keyed or otherwise secured to the shaft 22.

The movable frame 21 is provided with ways or slide bearings 26 and 27 in which 90 slides 28 and 29 constituting propeller carriers are operatively received. Each of the propeller carriers is adapted to support and carry the propeller blades or vanes. Any

number of propeller vanes or blades may be 95 provided but for the sake of simplicity only one pair is shown for each slide. As clearly shown in Figures 2 and 3 a pair of propeller blades, designated at 30 and 31 are

pivotaly connected to the propeller carrier 100 28 and similarly a pair of propeller blades 32 and 33 are pivotaly connected to the carrier 29. These blades are all of identical construction and as shown in the drawings are pivotaly connected only at their inner ends.

The propeller blades 30, 31, 32 and 33 have associated therewith combined propeller guides and stops, designated at 105 34, 35, 36 and 37, respectively, which coact with their respective propeller blades to constrain them to proper movement and to confine their movement within the proper

limit. These combined guides and stops are all of identical construction so that a disclosure of one combined stop and guide serves to illustrate the construction of the 5 guide stops and guides 36, 37 as well. As shown in Figure 4, this combined guide and stop comprises a plurality of spaced bars 38, and by referring to Figure 2 it will be seen that these bars are secured at their inner 10 ends to the slide or carrier 27. At their outer ends the bars 34 are connected to a transverse bar 39 which is also connected to the slide or carrier by means of brace bars 40. The propeller blades freely operate 15 within the bars of their carriers and when they have been swung to full open position they engage and lie flush against the inclined bars 38. During their movement from feathering position against their 20 slide or carrier to open position, the side edges of these propeller blades engage the brace bars which thus also constitute guide bars.

Means is provided for simultaneously reciprocating the slides 27 and 28, whereby 25 operative propelling movement is imparted to the propeller blades 34, 35, 36 and 37. This means preferably includes a yoke 45 having arms 46 pivotally connected at their 30 ends with links 47, the links 47 and 48 being in turn pivotally connected to the slides 27 and 28. Intermediate its ends the yoke is pivotally connected as at 49 to one end of one section 50 of a telescoping shaft 52, 35 the remote end of the other section of the shaft being connected to a universal joint 53 which is also connected to one end of a pitman or connecting rod 54 the other end of which is pivotally connected to a crank 40 shaft 55. The crank shaft is driven from an engine by suitable motion transmission means or gearing.

The action of the propeller blades may be varied, that is to say, the propeller 45 blades may be controlled to exert either a forward pull, an upward lift or a combined pull and lift by tilting the movable frame 21. This tilting of the movable frame 21 is brought about by turning the supporting shaft 22. Any suitable means 50 may be provided for turning this shaft 22 and one such means is shown in Figures 2 and 3 and comprises a beveled gear 57 fixed to the supporting shaft 22 and meshed with a second beveled gear 58 carried at the end 55 of a controlling shaft 59, the control shaft being actuated by means of a hand wheel 60' fixed to a short shaft 61' and connected by a gear 62 with the control shaft 59.

60 Any number of power units may be organized with the aeroplane and they may be arranged in any desired or suitable manner. One arrangement is shown in Figure 1 above described and another arrangement 65 is shown in Figure 5. In Figure 5 the pow-

er units are designated generally at 60 and 61 and are arranged side by side at the forward end of the flying machine. These power units 60 and 61 are identical in all respects with the power unit shown in Figures 2 and 4 inclusive, and hereinafter described and these power units are operated by suitable motion transmission means or mechanism from the aeroplane or flying machine.

70 It is to be understood that suitable means is provided for releasably locking the movable frame 21 in any position to which it may be adjusted with respect to the stationary frame. Such releasable locking means may comprise a pivoted dog or pawl engageable with suitable notches or recesses formed in the shaft 22 or in a disk or other element fixed to the shaft, the pawl or dog being controlled by a hand lever and suitable motion transmission means from the seat or other convenient point of control. Again this releasable locking means may comprise a spring pressed locking rod 60' carried by the movable hand wheel and engageable 90 with the movable notches or sockets provided in the adjacent bearing.

75 I claim:

1. In a propulsion apparatus for use with aeroplanes, a frame having ways therein, slides operating in said ways and constituting propeller carriers, propeller blades pivotally connected to said slides, combined guides and stops carried by said slides and coacting with said propeller blades, and means for reciprocating said slides including a yoke having arms, links pivotally connected with the arms and with said slides, a telescopic shaft having one end pivotally connected to said yoke, a universal coupling 95 connected to the other section of said telescopic shaft, a crank shaft, and a pitman between said crank shaft and said universal coupling.

100 2. In a propulsion apparatus for use with aeroplanes, a main frame, a supporting shaft rotatably journaled in said main frame, a movable frame, spiders secured to said movable frame and having hubs fixed to said supporting shaft, reciprocating slides carried by said movable frame and propellers arranged upon said propeller carriers, and means to tilt said movable frame to vary the action of said propellers, said means comprising a beveled gear fixed to said supporting shaft, a control shaft having a beveled gear meshed with said first mentioned beveled gear and hand operated means for turning said control shaft.

105 3. In a propulsion apparatus for use with aeroplanes, a main frame, a supporting shaft rotatably journaled in said main frame, a movable frame, spiders secured to said movable frame and having hubs fixed to said supporting shaft, reciprocating slides car-

ried by said movable frame and propellers arranged upon said propeller carriers, and means to tilt said movable frame to vary the action of said propellers, and said means being cooperable with said supporting shaft.

4. In a propulsion apparatus for use with aeroplanes, a plane having a slide-way therein, a reciprocating slide operating in said slideway and constituting a propeller carrier, a pair of propellers pivotally con-

nected to said reciprocating slide, and a combined guide and stop for each of said propeller blades comprising a series of inclined bars secured at their inner end to said reciprocating slide, a transverse bar secured to the outer ends of said inclined bars, and combined guide and brace bars connected with said transverse bar and with said reciprocating slide. 15

ALBERT E. BEEBE.
